UNITED STATES PATENT OFFICE.

FRANK H. R. BLANK, OF CHICAGO, ILLINOIS.

VENDING-MACHINE.

1,058,144.

Specification of Letters Patent.

Patented Apr. 8, 1913.

Application filed February 12, 1912. Serial No. 677,114.

To all whom it may concern:

Be it known that I, FRANK H. R. BLANK, a resident of Chicago, in the county of Cook and State of Illinois, have invented certain 5 new and useful Improvements in Vending-Machines, of which the following is a full, clear, and exact description.

The invention relates to vending machines and designs to provide improved mechanism 10 for the automatic sale and distribution of goods and more particularly of the plunger operated type.

A further object is to provide improved mechanism that will release first one side 15 and then the other of a package, and thereby require but a very short stroke of the plunger to release a comparatively large package. This machine is adapted for the sale of paper drinking cups or the like.

20 The invention consists in the several novel features hereinafter set forth and more particularly defined by the claims at the end of the specification.

In the drawings: Figure 1 is a vertical 25 broken section. Fig. 2, Fig. 3 and Fig. 4 are detailed views of the delivery mechanism in various stages of operation. Fig. 5 is a section on line 5—5 of Fig. 1. Fig. 6 and Fig. 7 are detailed views of the coin-carrying and discharging mechanism.

The machine comprises, a case 8 having a base 9, a back 10, side walls 11—11 and a top 12 rigidly secured together. A front 13, having a window 14, a cut-away portion 15 35 and a slot 16, is removably secured to the case 8 by pins 17 in the bottom thereof which engage suitable holes in the base 9 and by a lock 18, which engages with the top portion 12. Rigidly secured within the 40 case 8, is a bottomless chute or receptacle 19 of suitable size and shape to hold a large number of packages 20. A portion of the front of said chute 19 is open so that a view of the pile of packages 20 may be had 45 through the window 14 and a weight 21 is placed on the top of said pile to force said packages downwardly in the chute 19 as fast as one is removed.

A package 22 about to be discharged is 50 held between an upwardly extending flange 23 on the bottom edge of the front of the receptacle 19 and a stationary wall or frame 24 longitudinally disposed in the case 8. A portion of the frame 24 below the 55 open end of a chute 19 is cut out as at 25 to permit the passage of said packages there-

through and ejector 26 is slidably mounted on said frame 24. Up-turned flanges 27 on the inner edges of the side portions of the carriage frame 24 engage the inner edges of the side rails of the ejector 26 and out-turned tongues 28 on said flanges 27 retain said ejector in sliding engagement on said frame and permit of a fore and aft movement. The stroke of an ejector 26 is limited by the ends of the flanges 27 which stop the front and rear rails of said ejector by engagement therewith when said ejector is shifted. On rear rails 29 of said ejector 26 are secured up-turned lugs 30 on which a 70 pivotal finger or dog 31 is tiltably mounted. Dog 31 is weighted so that normally it engages rail 29 and is disposed so that it may pass between inclined abutments 32, which support the rear of the stack of packages 75 20 on frame 24. The front of said dog 31 is formed with a down-turned lip 33 which is adapted to engage the rear edge of one of said packages 20. An up-turned plate 34 extends partially along one side of the ejector 26 in one piece therewith and to this a plate 35 is pivoted by a pin 36. The rear portion of this plate 35 acts as a weight and normally rests on one of the side rails of the ejector 26 so that the plate 35 is normally 80 85 held in a position shown in Fig. 2.

A plunger 37 is slidably mounted adjacent the plate 34 in guides 38 formed by the struck up portions on plate 24. A pin 39 on said plunger 37 engages a coil-spring 40 90 and holds said plunger in a forward position as shown in Fig. 5. Rigidly secured to the inner face of said plunger 37 and between it and the plate 34 is a plate 41 of such a size that the space between its 95 rear edge and the front edge of the plate 35 will admit of the passage of a coin 42 when the plunger 37 is in its forward position. Above the space formed between the plates 41 and 35 and the plate 34 of the 100 side of the plunger 37 is a chute 43 which connects with the slot 16 in front 13.

A coin 42 is placed in the slot 16 and rolls down a chute 43 and its edges engage with the plates 35 and 41 and it is arrested 105 by an abutment or stop 44 on the plate 35. The plunger 37 is then pushed inwardly and the plate 41 moves the coin 42 which is engaged by the plate 35 so that the ejector 26 is moved backward a short distance. 110 This movement causes the inner edge of the front of said ejector to engage the edge of

the package 22 and moves said package from engagement between the flange 23 and the frame 24 and beyond the inner edge of said frame 24 so that it drops down onto a suitable slide 45 and out through the cut-away portion 15 in the front 13 of the case. As the package 22 is freed, the front of the lowest package of the pile 20 drops onto the frame 24 and when the ejector 26 is shifted forwardly, after the plunger 37 is released, the dog 31 engages the rear edge of the package at the bottom of the pile 20 and moves it forward so that its front edge is held between the flange 23 and the frame 24. This shifting of the ejector is accomplished by an offset 46 on the front of plate 34 engaging with the front of the plate 41 so that when the plunger 37 is pushed by the spring 40, the ejector 26 is also moved. The plate 47 is secured on an offset 48 on the underside of a plate 24 and is weighted so that its rear upper edge is normally held against the underside of said frame 24. The lug 49 on plate 47 is arranged to slip under an abutment 50 on plate 35 when ejector 26 is shifted rearwardly but to engage said abutment when the ejector 26 is returned. This is accomplished by plate 47 being tilted when the abutment 50 engages a trip-lug 49 in the first instance, but owing to the upper rear edge of the plate 47 being held normally against the frame 24 said plate 47 is held from tilting when the ejector 26 is moved forwardly. The abutment 50 engages the lug 49 thus securely held and a further forward movement of the ejector 26 causes the plate 35 to turn on its pivot and thus turning to discharge the coin 42 through a chute 52 and into a coin-box 53 on the bottom of the case 8. It will thus be seen that each time a coin is placed in the machine and the plunger operated, one package will be discharged and another placed in readiness for the next operation of the machine, the coin discharged onto a receptacle for the purpose and the whole mechanism placed in readiness for the next operation. If, however, the plunger is operated without placing a coin in the slot, the plunger alone is shifted and no engagement between it and the ejector takes place so that the ejector remains unmoved and no package is discharged.

55 The improved mechanism is one adapted to be constructed of sheet metal the parts in which a comparatively large package may be handled.

Having thus described the invention, what 60 I claim as new and desire to secure by Letters Patent, is:

1. In a vending machine, the combination of a case, a chute for the articles, slideable means for holding the front and rear edges 65 of the articles, an ejector, and means on the

ejector to successively release the front and rear edges of the articles to discharge them.

2. In a vending-machine, the combination of a case, a chute for the articles, a frame, an ejector slidably mounted on the frame 70 and formed to permit an article to pass therethrough, means on the frame for holding the front and rear edges of the articles, and means for the ejector to successively release the front and rear edges of the articles 75 and discharge them.

3. In a vending-machine, the combination of a case, a chute for the articles, a slideable ejector formed to permit a package to pass therethrough, means for holding the front 80 and rear edges of the articles, means on the ejector to successively release the front and rear edges of the article to permit it to fall through the ejector, and a frame in the case 85 on which the ejector is slidably mounted.

4. In a vending machine, the combination of a case, a frame within said case, a chute for the articles, a slideable ejector formed to permit the packages to pass therethrough, means for holding one of the edges of the 90 article, an inclined abutment on the frame, for supporting the opposite edge, and means on said ejector to successively release the front and rear edges of the articles and discharge the article. 95

5. In a vending machine, the combination of a case, a frame within said case, a chute for the articles, an ejector slidably mounted on the frame and formed to permit said articles to pass therethrough, means for holding the front and rear edges of the articles, means on said ejector to successively release the front and rear edges of the articles and permit them to fall through the frame, and a tilting finger on the ejector. 100

6. In a vending machine, the combination of a case, a chute for the articles, a slideable ejector, having an aperture therein to permit the articles to pass therethrough, means for holding the front and rear edges of the articles, means on said ejector to successively release the front and rear edges of one article and permit said article to fall through said ejector, and a frame in the case having an opening therein through which articles 115 may fall and having its edges struck-up to form guides for the ejector.

7. In a vending machine, the combination of a case, a chute for the articles, a slideable ejector having an aperture therein to permit articles to pass therethrough, means for holding the front and rear edges of the articles, means on said ejector to successively release the front and rear edges of one article and permit it to fall through the ejector, 120 and a frame in the case having an opening therein through which articles may fall, having its edges struck-up to form guides for the ejector and out-turned lips on the struck-up portions. 125

8. In a vending machine, the combination of a case, a frame within said case, a chute for the articles, an ejector slidably mounted on said frame and having an aperture to permit the articles to pass therethrough, means for holding the front and rear edges of the packages, means on said ejector to successively release the front and rear edges of the articles and permit them to fall through said ejector, a plunger for operating the ejector, struck-up portions on the frame to guide the plunger.
9. In a vending machine, the combination of a case, a rectangular frame in said case, a rectangular ejector mounted to slide on 15 said frame, said frame having upturned edges for guiding said ejector, said edges having indented portions for holding said ejector on said frame, one end of said ejector having an upturned abutment for supporting the merchandise, a pivoted finger mounted on said ejector, and means for operating said ejector.
- 10 through said ejector, a plunger for operating the ejector, struck-up portions on the frame to guide the plunger.
9. In a vending machine, the combination of a case, a rectangular frame in said case,
